UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

ELECTRIC HEATER.

1,307,556.

Specification of Letters Patent. Patented June 24, 1919.

Application filed February 21, 1918. Serial No. 218,400.

To all whom it may concern:

Be it known that we, FRANK KUHN and JAY A. HAND, both citizens of the United States of America, residing at Detroit, in the county of Wayne and State of Michigan, have invented certain new and useful Improvements in Electric Heaters, of which the following is a specification, reference being had therein to the accompanying drawings.

10 The invention relates to luminous electric heaters and relates particularly to electric heaters of the type which may be employed as a substitute for the ordinary fireplace, and are adapted to be set into a wall of a room.

15 It is the object of the invention to provide a luminous electric heater comprising a unit including one or more heating elements and a mounting for said elements and their switches; and further comprising a casing 20 for receiving the unit but adapted to be set into a wall independently of the unit.

The invention further consists in certain structural features hereinafter fully set forth.

25 In the accompanying drawings:

Figure 1 is a front view of an electric heater embodying the novel features of the present invention;

Fig. 2 is a vertical sectional elevation of the heater, the section being taken on line 2—2 of Fig. 1;

Fig. 3 is a rear view of the heating unit omitting the casing of the heater.

In these views the reference character 1 designates a casing adapted to be set into a wall flush with the surface thereof and having at its top and bottom a plurality of lugs 2 whereby the casing may be secured to the wall; 3 is a mounting for one or more heating elements, which elements preferably will have the form of a series of electric bulbs 4, the central portion of the mounting 3 being depressed to allow positioning of said bulbs within the casing 1. The bottom of 45 the depressed central portion of the mounting 3 is formed with orifices 5 through which the bulbs 4 are passed for engagement with sockets 6. These sockets are carried by a bar 7 secured to the mounting 3 therebeneath,

the mounting being spaced sufficiently above the bottom of the casing 1 to form a chamber receiving said sockets. The mounting 3 is peripherally formed with a flange 8 which seats upon the front edges of the casing 1 and cap screws 9 are passed through the flange 8 and through flanges 10, inwardly projecting from the side walls of the casing to rigidly secure the mounting to the casing. Opposite the sockets 6 there is formed in the flange 8 an apertured boss 11 which houses a switch 12 for controlling the heating elements, said switch being supported by one or more brackets 13 projecting forwardly from the bar 7. As a provision for the circulation of air between the mounting 3 and the casing 1, orifices 14 are formed in the flange 8 in communication with the chamber below the central portion of the mounting and the space above said central portion within the casing is vented through orifices 15 in said flange. To further insure against the back wall of the casing 1 being overheated there is mounted upon said wall in a spaced relation thereto, a metallic plate 16 disposed oppositely to the depressed central portion of the mounting. 17 is an orifice in the bottom of the casing 1 through which the conductors 18 may be introduced into the same.

By the above described construction the installation of an electric heater of the wall type is facilitated, since during the erection of a building the casing 1 may be set into a wall and the conductors drawn thereinto and the heating unit itself need not be mounted in said casing until the construction work on the building is completed.

By location of the switch 12 in a boss 11, as above described, said switch is well safeguarded against accidental damage.

What we claim as our invention is:

An electric heater, comprising a casing, and a unit detachably connected to said casing comprising a plurality of luminous heating elements, and a mounting for said elements peripherally flanged to engage the edges of the casing having a depressed central portion to receive said elements and to

dispose the same within the casing, an air passage being formed above, below and at the rear of said depressed portion, the top and bottom flanges of the mounting being orificed to communicate with said air passage, a bar secured to the depressed portion beneath the same, and a plurality of socket

members mounted upon said bar and engaged by said luminous elements.

In testimony whereof we affix our signatures,

FRANK KUHN.
JAY A. HAND.
